UNITED STATES PATENT OFFICE.

NICHOLAS W. WEBB, OF NEW YORK, N. Y.

LOCK.

No. 816,405.

Specification of Letters Patent.

Patented March 27, 1906.

Application filed November 1, 1904. Serial No. 230,904.

To all whom it may concern:

Be it known that I, NICHOLAS W. WEBB, a citizen of the United States, and a resident of the city of New York, borough of the Bronx, 5 in the county and State of New York, have invented a new and Improved Lock, of which the following is a full, clear, and exact description.

The invention relates to locks and latches for doors and the like; and its object is to provide a new and improved lock arranged to prevent unauthorized persons from unlocking the door or other part on which the lock is used, the main bolt of the lock being held 15 against retraction when the door is in a closed position unless the operator has the proper key or can turn the knob on the inside of the door.

The invention consists of novel features 20 and parts and combinations of the same, as will be more fully described hereinafter and then pointed out in the claims.

A practical embodiment of the invention is represented in the accompanying drawings, 25 forming a part of this specification, in which similar characters of reference indicate corresponding parts in all the views.

Figure 1 is a rear face view of the improvement, the rear cover being removed. Fig. 2 30 is a like view of the same, showing the main and auxiliary bolts in retracted position, parts being broken out. Fig. 3 is a like view of the same, showing the parts in position when the door is closed, the main bolt being 35 in a projected position in engagement with the keeper and the auxiliary bolt being in a retracted position and held therein by the keeper. Fig. 4 is an inverted sectional plan view of the improvement on the line 4-4 of 40 Fig. 1. Fig. 5 is a sectional plan view of the same on the line 5-5 of Fig. 1, and Fig. 6 is an inverted plan view of the same on the line 6-6 of Fig. 1.

In the casing A, secured to the door B at 45 the inside thereof, is mounted to slide the main bolt C, normally held in a projected position by springs D for the beveled head of the bolt to engage a keeper or striking-plate E, secured to the jamb of the door, as indicated in 50 Fig. 3. The main bolt C is provided with parallel guide-rods C', mounted to slide in a bearing A', attached to the post A² of the casing A, and on the said guide-rods C' are coiled the springs D, abutting with their forward 55 ends on the head of the main bolt C and rest-

ing with their rear ends on the said bearing A'. The rear ends of the guide-rods C' are connected with each other by a yoke C², adapted to be engaged by the retracting mechanism for the main bolt C, the said retracting mechanism consisting of a cam F' on a cam-plate F, having its hub F² journaled in the casing A, the inner end of the hub having a lug F³, fitting a recess in the inner end of the hub of a manually-controlled knob G, 65 as plainly indicated in Fig. 4, and the outer end of the hub F² is provided with a recess F⁴, adapted to be engaged by the cam or bit H' of a key-controlled tumbler-lock H of any approved construction, preferably, however, 70 of the construction shown and described in the application for Letters Patent of the United States filed by me under even date herewith, Serial No. 230,905. By turning the knob G or the bit H' when the latter is engaged with the recess F⁴ the main bolt C can be retracted against the tension of its 75 springs D. The outward sliding motion of the main bolt C is limited by the yoke C², abutting against a stud A⁷, fixed on the case A. 80

When the main bolt C is in a projected position, as indicated in Figs. 1 and 3, then it is locked in this position by a locking-lever I, fulcrumed on the post A², previously mentioned, and having its forward end I' abutting 85 against a lug C⁸, projecting rearwardly from the head of the bolt C. A spring I² presses the locking-lever I to normally hold the same in a locking position—that is, with the end I' abutting against the lug C⁸. The rear end of 90 the locking-lever I is provided with a tooth or lug I³, normally fitting a recess F⁶, formed in the peripheral face of the cam-plate F of the retracting mechanism, and the said recess F⁶ is so arranged relative to the cam F' 95 that when the cam-plate F is turned the recess F⁶ acts on the tooth I³ to impart a swinging motion to the locking-lever I to move the end I' thereof out of engagement with the lug C⁸ previous to the cam F' engaging the yoke C². Thus from the foregoing it will be seen that the locking-lever I is swung out of engagement with the lug C⁸ previous to the reTRACTING mechanism acting on the bolt C to retract the same—that is, the main bolt C is 100 unlocked before it is retracted—on turning the knob G or actuating the tumbler-lock H, as previously explained.

The locking-lever I is also controlled by an auxiliary bolt J, having its beveled head J' 110

superimposed on the head of the main bolt C, the bevel of the head J' being, however, somewhat in advance of the bevel of the head of the main bolt C, so that on closing the door 5 the beveled head J' of the bolt J is acted on by the keeper or striking-plate E in advance of the head of the main bolt C, and during this retracting movement of the auxiliary bolt J a swinging motion is imparted to the locking-lever I to disengage the end I' from the lug C³ to unlock the main bolt C for the latter to be retracted when coming in contact with the keeper or striking-plate E on closing the door.

15 The auxiliary bolt J is provided with a guide-rod J², fitted to slide at its rear end in a bearing A⁴, held in the casing, (see Fig. 6,) and on the said guide-rod J² is coiled a spring J³, resting with its inner end on the bearing 20 A⁴ and pressing with its forward end on the head J' of the bolt J to hold the latter normally in a projected position. On the auxiliary bolt J is held a friction-roller J⁴, adapted to engage a projection K³, into which projects a stud A⁵, forming part of the casing, 25 the stud constituting the pivot for the arm K to swing on. The arm K is provided near its free end with a lug K³, resting on a lug I⁴, formed on the locking-lever I, so that when 30 the auxiliary bolt J is retracted upon coming in contact with the keeper E then the roller J⁴ imparts a swinging motion to the arm K, which by the lug K³ engaging the lug I⁴ imparts a swinging motion to the locking-lever I to swing the free end I' thereof out of engagement with the lug C³ to allow of the retraction of the main bolt C by the head of the bolt coming in contact with the keeper immediately after the head J' of the auxiliary 35 bolt J has been pushed rearward by coming in contact with the keeper. (See Fig. 2.) Both bolts C and J are moved in a complete retracted position until the head of the bolt C finally passes into the opening of the keeper to allow the springs D to project the main bolt into the opening of the keeper to hold the door in a locked position. The head 40 J' of the auxiliary bolt J remains in contact with the face of the keeper E and is consequently not projected after the door is closed, but remains in the retracted position during the time the door is closed.

When the main bolt C is projected forwardly to engage the keeper E on closing 45 the door, then the locking-lever I immediately swings back to its normal position by the action of its spring I to reengage the end I' with the lug C³ to hold the main bolt C locked in a projected position. When the 50 locking-lever I swings back to its normal position, as mentioned, it imparts an upward swinging motion to the arm K, it being understood that during the retraction of the auxiliary bolt J its roller J⁴ has passed the 55 projection K', and hence the arm K swings

back to a normal position with the spring-pressed locking-lever. As the locking-lever I remains in this locked position while the door is closed, it is evident that the main bolt cannot be retracted by an unauthorized person 70 trying to tamper with the lock, as it is necessary to first project the auxiliary bolt J, and this cannot be done unless the door is opened and the head J' of the said auxiliary bolt moves out of engagement with the face of the 75 keeper E.

It is understood that the main bolt C can be retracted by a person having the proper key inserted in the tumbler-lock H or by a person on the inside of the door manipulat- 80 ing the knob G, as previously explained.

On the head J' of the auxiliary bolt J is formed a shoulder J⁵, engaged by the back of the head of the main bolt C, so that when the latter is retracted by manipulating either the 85 knob G or the tumbler-lock H then the auxiliary bolt J is retracted with the main bolt, owing to the latter being in engagement with the shoulder J⁵. (See Fig. 2.)

The free end I' of the locking-lever I rests 90 against the under side of the lug C³ of the main bolt during the time the latter is retracted, (see Fig. 2,) and as soon as the bolt C shoots out the lever I swings back to its normal locking position by the action of the 95 spring I², and in doing so it swings the arm K back to a normal position, the roller J⁴ being in the rear of the projection K', permitting such movement of the arm K. The latter has the elongated slot to allow lengthwise 100 movement of the arm at the time the auxiliary bolt J is projected outward by its spring J³, the roller J⁴ then engaging the projection K' to carry the arm K forwardly and slightly downwardly for the roller J⁴ to finally 105 clear the projection K' immediately previous to the return of the locking-lever I and the upward swinging of the arm K to normal position.

A snap-catch L is provided for engagement 110 with the yoke C² (see dotted lines, Fig. 2) to permanently lock the main bolt C, and with it the auxiliary bolt J, in retracted positions. The snap-catch L is fulcrumed at L' on the 115 inside of the casing A and receives a swinging motion from the slide L³, provided with a knob L⁴, extending to the outside of the casing A. A spring-pressed dog N, fulcrumed on the slide, is adapted to engage either side of a lug A⁶, formed on the casing A (see Fig. 120 5) to hold the slide in either a forward or rearward position. When the bolt C and the auxiliary bolt J are retracted and the knob L⁴ is pushed rearward, then the catch L is 125 swung in position on the forward face of the yoke C² (see Fig. 2) to hold the bolt C, and with it the auxiliary bolt J, permanently in retracted positions, it being understood that the shoulder J⁵ does not allow the bolt J to shoot out as long as the main bolt is retracted. 130

When the knob L³ is pushed forward, the catch L is swung out of engagement with the yoke C² to release the main bolt C.

Having thus described my invention, I 5 claim as new and desire to secure by Letters Patent—

1. In a lock, the combination with a keeper, of a main bolt for engaging the keeper, a locking device for locking the main bolt in 10 a projected position, and an auxiliary bolt for engagement with the said keeper in advance of the main bolt when closing the door, the said auxiliary bolt actuating the said locking device, to unlock the main bolt for 15 the latter to be in position to be retracted, the keeper being arranged to hold the said auxiliary bolt in a retracted position while the door is closed.

2. A lock provided with a spring-pressed 20 main bolt, a locking device for holding the said main bolt against retraction, an auxiliary bolt extending beyond the main bolt when both bolts are projected, a pivoted arm arranged to receive a swinging motion from 25 the said auxiliary bolt and to actuate the said locking device, and a manually-controlled retracting mechanism for the said main bolt, controlling the said locking device independent of the said auxiliary bolt and 30 the said arm.

3. A lock comprising a keeper, a spring-pressed main bolt, a spring-pressed locking-lever for locking the said main bolt against retraction, an auxiliary bolt extending beyond the said main bolt when both bolts are 35 projected, and a pivoted arm controlled by the said auxiliary bolt and engaging the said locking-lever, to swing the latter out of engagement with the main bolt.

4. A lock comprising a keeper, a spring-pressed main bolt, a spring-pressed locking-lever for locking the said main bolt against retraction, an auxiliary bolt extending beyond the said main bolt when both bolts are 45 projected, a pivoted arm controlled by the said auxiliary bolt and engaging the said locking-lever, to swing the latter out of engagement with the main bolt, and a manually-controlled retracting mechanism for retracting 50 the said main bolt independent of the said auxiliary bolt, the said retracting mechanism also controlling the said locking-lever independent of the auxiliary bolt and its pivoted arm.

5. A lock comprising a keeper, a spring-

pressed main bolt, a spring-pressed locking-lever for locking the said main bolt against retraction, an auxiliary bolt extending beyond the said main bolt when both bolts are projected, a pivoted arm controlled by the 60 said auxiliary bolt and engaging the said locking-lever, to swing the latter out of engagement with the main bolt, and a cam-disk adapted to be turned and having means for engaging the main bolt with a view to retract 65 the same, the said disk having a peripheral notch for engagement by a tooth on the said locking-lever.

6. A lock, provided with a spring-pressed main bolt, a pivoted and spring-pressed locking-lever for locking the main bolt projected, a spring-pressed auxiliary bolt, and means for actuating the locking-lever from the auxiliary bolt to release the main bolt, when the auxiliary bolt is pushed inward. 70

7. A lock provided with spring-pressed main bolt, a pivoted and spring-pressed locking-lever for locking the main bolt projected, a spring-pressed auxiliary bolt, and a pivoted arm operated by the auxiliary bolt and actuating the locking-lever to release the main bolt when the said auxiliary bolt is pushed 80 inward.

8. A lock provided with a main bolt, a locking device for the main bolt, an auxiliary 85 bolt, means for actuating the locking device from the auxiliary bolt when said bolt is pushed inward, and means for permanently locking the main bolt and with it the auxiliary bolt in retracted positions. 90

9. A lock provided with a main bolt, an auxiliary bolt, and means for permanently locking the auxiliary bolt in a retracted position.

10. A lock provided with a main bolt, a locking device for the said main bolt, to hold the latter against retraction, an auxiliary bolt for controlling the said locking device, and manually-controlled means for retracting the auxiliary bolt and locking it permanently in a retracted position and freeing the 100 said locking device.

In testimony whereof I have signed my name to this specification in the presence of two subscribing witnesses.

NICHOLAS W. WEBB.
